BURNER FOR CORROSIVE FLUIDS

Do Jefferson, Houston, Tex., assignor to The Texas Company, New York, N. Y., a corporation of Delaware

Application February 11, 1933, Serial No. 656,258

1 Claim. (Cl. 158—4)

This invention relates to an apparatus for burning corrosive liquids and fluids of the type of acid sludge in a manner which will avoid contact of the unconsumed sludge with any parts of the burner or furnace except the outlet nozzle for the sludge.

One of the main objects of the invention is to provide a burner for supplying a curtain of steam onto which the corrosive fluids are discharged, the steam breaking the fluids up into small particles and carrying these particles into the fire box of the furnace as they are consumed.

The above and other objects of the invention will appear more fully from the following description when considered in connection with the drawing wherein:—

Fig. 1 is a longitudinal sectional view of a furnace, illustrating one form which the invention may assume.

Fig. 2 is a vertical sectional view of the furnace taken on the line 2—2 of Fig. 1.

Acid sludge constituting the residue from the acid treatment of lubricating oil or other hydro-carbon materials may or may not be preliminarily treated as by being cut back with a thin gas oil or the like, the sludge then being settled for the recovery of as much of the sulphuric acid as possible. The remaining material, after the recovery of the acid, has substantially no economic value and is usually in a liquid state, containing sufficient volatile matter to burn without auxiliary heat, provided it is properly introduced and distributed in a hot fire box as described herein. This sludge, however, still retains sufficient acid to remain highly corrosive to the burner and other parts of the furnace with which it comes in contact, particularly while in a heated state. If the sludge is not completely consumed, there is danger of particles of this material collecting in the furnace to form a corrosive body which injures the furnace. It is particularly important to prevent bodies of the material from coking and collecting in the furnace since these bodies may be subsequently discharged from the stack as incompletely consumed corrosive lumps which constitute a hazard from fire and fumes in the vicinity of the furnace.

These difficulties are avoided in the burner disclosed herein.

In carrying out my invention, any typical furnace may be employed. As shown, the furnace 4 includes a fire box 6 and a partition wall 8 for increasing the temperature in the forward part of the furnace. The furnace wall 8 and floor 9 of the fire box may be cooled by a flow of com-

bustion promoting air, as shown, this construction having the advantage of supplying only pre-heated air for facilitating the combustion of the fluids introduced. Additional combustion promoting air may be supplied to the furnace in the usual manner if desired.

The burner includes a nozzle 10 connected with a steam supply pipe 12 leading to a suitable source of supply controlled by the valve 15. The nozzle 10 is preferably flattened at its outer or discharge end so that a relatively thin fan-shaped sheet of steam will be maintained in the furnace as indicated at 14.

The material to be burned, that is, the acid sludge, is discharged into the fire box 6 by means of a nozzle 16 connected to a fluid supply pipe 18 leading to the source of supply. The nozzle 16 is of the same general type as 10 and is designed to discharge the corrosive fluid in a thin fan-shaped sheet 17 directly onto the sheet of steam 14 in the fire box. To this end, the nozzle 16 is placed adjacent the nozzle 10 but above the same, the nozzle 16 being inclined downwardly to a slight extent, if preferred, in order that the flow of steam may uniformly pick up the sheet of corrosive fluid and break it up into small particles while carrying this fluid into the fire box where it is consumed.

It will be understood that the sludge is supplied to the pipe 18 in a substantially steady stream and under suitable pressure as by means of the usual supply pump. The supply may be regulated by controlling the pump or, if preferred, a valve may be placed in the feed line adjacent the outlet from the line. A substantially even supply of the sludge is necessary in order that the fire box retain an even heat necessary for the efficient consumption of the materials referred to. This temperature should remain between 1500° and 2500° F. for the most effective operation.

An auxiliary burner shown as a gas burner 20 is utilized for preheating the fire box to red heat before the introduction of the sludge. The auxiliary heat may be continued at a reduced rate if necessary for the prompt and complete combustion of the sludge.

An apparatus constructed as herein disclosed has the particular advantage that the corrosive fluids do not at any time contact with any portion of the apparatus, except the pipes and nozzle for conducting and discharging these fluids into the fire box. In the fire box the sheet of steam picks up the sludge discharged in a thin sheet thereon, breaking it up into fine particles

which are immediately consumed, thus preventing the unconsumed particles from being deposited upon the walls of the fire box or on the burner. Since the sludge nozzle 16 is entirely distinct from and separated from the steam nozzle 10, there is no contact of the sludge with the steam nozzle and no contact with any metal parts after the steam and sludge are brought into contact. The burner has been found efficient in operation and substantially free from deterioration produced by the corrosive character of the sludge.

While reference is made herein to a particular material to be consumed, it will be understood that the invention is not so limited and that the apparatus is useful for disposing of any other similarly corrosive fluids.

Obviously many modifications and variations

of the invention, as hereinbefore set forth, may be made without departing from the spirit and scope thereof, and therefore only such limitations should be imposed as are indicated in the appended claim.

5
I claim:

In a furnace formed with a fire box for burning corrosive liquids, a steam nozzle constructed to provide a fan-shaped jet of steam in said fire box, a liquid discharge nozzle positioned adjacent but out of contact with said first-named nozzle for discharging corrosive liquids in a fan-shaped stream upon said jet of steam and a burner for fluid fuel positioned beneath said nozzles and adjacent the same for facilitating the 15 combustion of said corrosive liquids.

DO JEFFERSON.
